* cited by examiner

Primary Examiner—Ian Simmons*Assistant Examiner*—Anna Burmeister(74) *Attorney, Agent, or Firm*—Knobbe, Martens, Olson & Bear, LLP.(57) **CLAIM**

The ornamental design for a bottle, as shown and described.

DESCRIPTION

FIG. 1 is a top, front, left side perspective view of a bottle embodying my new design;

FIG. 2 is a top, rear, left side perspective view thereof;

FIG. 3 is a front elevational view thereof;

FIG. 4 is a right side elevational view, the left side elevational view being a mirror image thereof;

FIG. 5 is a top plan view thereof; and,

FIG. 6 is a bottom, front, left side perspective view thereof. The broken lines shown in the drawings represent contour lines.
